CLAIM

The ornamental design for container with elongated lip, as shown and described.

DESCRIPTION

FIG. 1 is a front perspective view of a container with elongated lip showing my new design;

FIG. 2 is a top plan view thereof;

FIG. 3 is a first side view thereof, the opposite side being a mirror image;

FIG. 4 is a first end view thereof, the opposite end being a mirror image; and,

FIG. 5 is a bottom plan view thereof.
